Attorney

UNITED STATES PATENT OFFICE.

CALVIN A. MESSINGER, OF ROCK ISLAND, ILLINOIS.

BRICK-TONGS.

1,364,128.

Specification of Letters Patent.

Patented Jan. 4, 1921.

Application filed March 24, 1920. Serial No. 368,828.

To all whom it may concern:

Be it known that I, CALVIN A. MESSINGER, a citizen of the United States, residing at Rock Island, county of Rock Island, and 5 State of Illinois, have invented certain new and useful Improvements in Brick-Tongs, of which the following is a specification.

My invention relates to brick tongs, that is, to devices for gripping a plurality of 10 bricks to facilitate handling and carrying the same.

The object of my invention is to provide a device of the character mentioned which will firmly grip the bricks without chipping or 15 crushing the same. A further object of my invention is to provide a device as mentioned which may be readily adjusted to grip a greater or less number of bricks, or bricks or tile of different sizes. Further 20 objects of my invention are to provide a device of the character under consideration which shall be of simple construction, of low cost to manufacture, of comparatively light weight and which will not readily get out 25 of order. Other objects will appear herein-after.

With these objects in view my invention consists generally in a device of the class mentioned comprising a pair of substantially 30 parallel slidably connected bars, and gripping jaws on the remote ends of said bars, a lever pivotally connected to each of said bars, and bent to form a handle substantially parallel with said bars. My invention further consists in a device as mentioned further characterized by an adjustable connection between said lever and one of said bars whereby the device may be adjusted to vary the width between the jaws. 35

My invention further consists in various details of construction and arrangements of parts all as will be fully described herein-after and particularly pointed out in the claims.

My invention will be more readily understood by reference to the accompanying drawings forming a part of this specification and in which,

Figure 1 is a side elevation of the device 50 embodying my invention, and,

Fig. 2 is a perspective view of the same.

Referring now to the drawings 1 and 2 indicate a pair of substantially parallel bars, provided on their remote ends with gripping 55 jaws 3 and 4 respectively. The bar 1 is sub-

stantially straight throughout its length and is adapted to rest upon the upper faces of the bricks or tile 5 as indicated in Fig. 1. Its inner end, that is, the end opposite the jaw 3, is bent upwardly and formed into an eye 6 through which the bar 2 is freely slideable. The bar 2, a short distance from the jaw 4, is bent upwardly and then inwardly as indicated at 7 in order to extend through the eye 6 and be positioned substantially 65 parallel to the bar 1.

Pivots connected, as at 8, to the bar 1, is a lever 9 comprising a substantially vertical bifurcated portion 10, and a horizontal portion 11. The end of the bar 2 extends 70 within the bifurcated portion 10 and is pivotally connected thereto by a removable pin 12. The bar 2 is provided with a series of apertures 13, adjacent its inner end to receive the pin 12, by which arrangement it is 75 obvious that the distance between the jaws 3 and 4 may be readily adjusted.

The jaws are broadened, flat faced members which will not injure the surfaces of the 80 bricks or tile. By having the members slidably connected these jaws are brought into contact with the faces of the bricks substantially parallel thereto and hence will not dig into and mar the bricks as is the case with similar devices in which the jaws or jaw 85 holding devices are pivotally connected. The operation of the device is obvious.

I claim:

1. A device of the class described comprising a pair of substantially parallel slidably connected members, jaws on the remote ends of said members and a lever pivotally connected to said members, substantially as described.

2. A device as set forth in claim 1 in which the lever comprises a substantially vertical bifurcated portion embracing said members and a horizontal handle portion, substantially as described.

3. A device as set forth in claim 1 further characterized by an adjustable connection between said lever and one of said members substantially as described.

4. A device of the class described comprising a pair of substantially parallel bars, jaws on the remote ends of said bars, an eye on one of said bars through which the other bar is freely slideable and a lever pivotally connected to said bars substantially as described.

5. A device as set forth in claim 4 further characterized by an adjustable connection between said lever and one of said bars.
6. A device of the class described comprising a horizontal bar, a jaw on one end thereof, the opposite end of said bar being bent upwardly and provided with an eye, a second bar provided at one end with a jaw, said bar being bent upwardly and then inwardly into substantial parallelism with the first said bar and sliding freely through said eye, a lever pivotally connected to the first said bar and a pivotal connection between said lever and the second mentioned bar substantially as described.
- 10 7. A device as set forth in claim 6 in which

said lever comprises a bifurcated substantially vertical portion embracing said bars and the horizontal handle portion.

8. A device as set forth in claim 7 in which one of said bars is provided with a plurality of apertures and a removable pin extending through said lever and selectively engaging in one of said apertures as and for the purpose specified.

20 In testimony whereof I have signed my name to this specification in the presence of two subscribing witnesses.

25 CALVIN A. MESSINGER.
